UNITED STATES PATENT OFFICE.

JOSEPH HOLLIS, OF LEICESTER, ENGLAND.

WOOD-TRIMMER AND THE LIKE.

1,144,844.

Specification of Letters Patent. Patented June 29, 1915.

Application filed May 1, 1913. Serial No. 764,868.

To all whom it may concern:

Be it known that I, JOSEPH HOLLIS, subject of George V, King of Great Britain and Ireland, and residing at 1 St. Pauls road, 5 Leicester, England, have invented certain new and useful Improvements in Wood- Trimmers and the like, of which the following is a specification.

This invention relates to wood-trimmers 10 and the like.

The object of the invention being to provide means for exposing the unused and sharper edges of the knives in the wood trimmer to the wood to be cut as the cutting 15 edges become dull, I propose to accomplish this result by having the knives adjustably held on the knife carrier and adapted to be lowered to bring the higher portions into use. To this end, I provide at the rear edge 20 of the table a downwardly extending gap which gives clearance for the knives when they are lowered.

A further object being to provide means 25 for cutting angles of more than one inclination, (what I term "compound" angles) as frequently required, for example, by joiners in cutting cornice molds or by pattern makers in cutting fillets. Now, by this invention, I can readily and accurately cut the 30 mold at any angle. To do this I take advantage of one of the beveled edges which it is customary to form on the edges of the molding, by using it to automatically determine the angle at which the molding is to be 35 cut. For use in conjunction with said beveled edges, I provide a pair of shoes furnished with sliding stops. The fence having been set to the required angle, and the lower beveled edge of the molding having 40 been brought hard up thereto I then bring the corresponding shoe and stop into contact with the molding so that the upper edge of the latter rests in the angle between the sliding stop and the underside of the shoe, 45 whereupon the molding is ready to be cut.

A further object of this invention is to enable boards, molded skirtings etc., which are of greater width than the vertical capacity of the machine to be beveled or mitered. To this end the machine is provided with a removable canting or sloping table or frame which is capable of angular movement and which can be secured at any angle or slope depending upon the angle of

cut required to be made. In using the canting table the board or the like is placed thereon with the end to be cut in the angle between the horizontal table of the machine and the knives.

In using wood-trimmers it has been found 60 that, other conditions remaining the same, the same angle of cut is not obtained with hard wood as with soft wood, nor with sharp knives as with dull knives, nor with wood of regular cross-section as with wood 65 of irregular cross-section, this being due to the varying resistance which the wood offers to the knives while it is being cut. Consequently, when the fence is always set to a given angle (more especially 45°) the angle 70 of cut obtained varies under the different conditions just referred to, with the result that the finished joint between two pieces of molding or the like is defective. Now, according to the present invention, this error 75 in the angle of cut is compensated for by means of devices whereby the fence can be quickly and finely adjusted to the correct angle.

In order that this invention may be clearly 80 understood and readily carried into effect, I will proceed to describe the same with reference to the accompanying drawings, where- in—

Figure 1 is a perspective view of a wood- 85 trimmer showing the gap at the rear for accommodating the knives when they are lowered, also the shoes and sliding stops, there being also shown in the machine a piece of cornice molding in position ready 90 for cutting. Fig. 2 shows the shoe and sliding stop separately in perspective. Fig. 3 is a front elevation more clearly showing the cornice molding resting between the fence and the shoe and stop. Fig. 4 is a perspec- 95 tive view of a modification in which the stops are formed in one piece. Fig. 5 is a part end elevation of the machine illustrated in Fig. 1 and more clearly shows the gap and the knife carriage. Fig. 6 shows in 100 front elevation a portion of a wood-trimmer with the canting table in position and a piece of stuff lying on the canting table. Fig. 7 is an end elevation of the left hand end of Fig. 6. Fig. 8 shows on a smaller 105 scale the canting table in perspective. Fig. 9 is a perspective view of a portion of a wood-trimmer and shows a stop-pin carry-

ing an adjustable set-screw for finely adjusting the fence. Fig. 10 is an enlarged view of the said stop-pin and adjustable set-screw; and Fig. 11 shows in plan the shape 5 of the hole in the horizontal table of the machine in which the stop-pin is supported.

Referring to Figs. 1 and 5 of the drawings, *a* is the gap above referred to, which is 10 preferably formed in a bracket *b* secured by means of set-screws *b'*, *b''* to the rear edge of the table *c* of the machine. The upper end of the outer limb *b²* of the bracket is provided with a groove *d* in which the lower edge of the knife carriage *e* slides, the upper 15 edge of the knife carriage being arranged to slide in an upper fixed guide *k*. A similar bracket is affixed to the opposite end of the table.

The knives shown at *e'*, *e''*, are secured to 20 the knife carriage *e*, *e*, by means of screws *e²*, *e²*, spaced equally apart and it will be seen that as their lower portions become dull or nicked they can be readily lowered into the gap *a* by removing the screws *e²*, *e²* and 25 secured in a fresh position by re-inserting the screws *e²*, *e²*. The broken lines in Fig. 5 show the knife lowered into the gap.

Describing now the shoes and sliding stops for holding cornice moldings, etc. in position for cutting, reference will be had to 30 Figs. 1, 2, and 3, wherein *h*, *h*, are the shoes which are provided with upright pins *h'*, *h'* and stops *h²*, *h²*, the latter being longitudinally adjustable in slots *h³*, *h³*, formed 35 in the shoes. These are adjusted to height to suit moldings of different depth by sliding their pins *h'*, *h'*, in sockets *j*, *j*, projecting forward from the upper fixed guide *k* of the knife carriage, the pins being held 40 in the sockets by means of thumb-screws *j'*, *j'*. The usual fence *l* having been swung around to the desired angle and fixed in its slot *l'* in the usual manner, and the lower beveled edge of the molding *m* having been 45 brought to bear against the fence as shown in Figs. 1 and 3, the shoe and stop are adjusted to it so that the top edge of the molding rests in the angle between the shoe and the stop as illustrated. In this position, the 50 molding is ready for cutting. It will be seen that by swinging both of the fences around to the proper angle and bringing both of the shoes and their stops in position both internal and external angles can be 55 cut on the moldings.

Sometimes, in carrying out this invention, instead of making the shoes separate, I may join the pins *h'*, *h'* together by a straight bar provided with a slot from end 60 to end in which to accommodate the stops *h²*, *h²* (see Fig. 4) but it is more convenient to have separate shoes, because if only one shoe is being used the other can be raised or completely removed so as to provide more 65 working space.

Referring now to Figs. 6, 7 and 8, the canting table therein shown comprises a frame *n* capable of angular movement in the angle between the table *c* and the knives *e'*, *e'*. The outer rail of the canting table 70 extends over the edge of the fences as illustrated and is provided with bolts *n'*, *n'* which pass through slots *l'*, *l'*, with which the fences are furnished. The bolts carry fly-nuts *n²*, *n²*. The curved edge of the 75 fences is marked with the angles 45°, 60° and 67½° (or other desired angles) and the canting table is secured at the required angle by screwing up the fly-nuts *n²*, *n²*. By removing such fly-nuts from their bolts, the 80 canting table can be at once removed.

Dealing now with Figs. 9, 10 and 11, *o* is the stop-pin which is provided with an adjustable set-screw *o'* and with a projecting pin or lug *o²*. The stop pin is intended to be dropped into one of the holes *c'* provided for it in the table *c* and is prevented from turning therein by its pin or lug *o²* fitting into a recess *c²* provided at one side of the hole. In operation the fence may first be set along the required angle line found engraved in the table *c*, the stop pin is then dropped into the corresponding hole *c'* and the set-screw *o'* is then adjusted so as to set the fence at the required angle. The lug *l'* on the fence is provided with a flat face with which the set-screw *o'* is maintained in constant engagement owing to the pull of the tension spring *p*. The fence having been finally adjusted, the clamping screw *q* 90 is screwed down tightly in the usual manner. 95

I claim:—

1. In a wood trimmer or the like, a table having a guideway, a member fixed to said table and having a guideway, a knife carrier supported in said guideways, knives attached to said knife carrier, fences provided on said table, means for securing said fences in position, a socket fixed to said member, a pin having a slotted shoe slidably mounted in said socket, a stop carried by and provided with means for securing it in position in said slotted shoe and means for fixing said pin in said socket. 105 110

2. In a wood trimmer or the like, a table having a guideway, a member fixed to said table and having a guideway, a knife carrier supported in said guideways, knives attached to said knife carrier, fences provided on said table, means for securing said fences in position, sockets fixed to said member, pins united by a slotted bar and slidably mounted in said sockets, stops carried by and provided with means for securing them in position in said slotted bar and means for fixing said pins in said sockets. 115 120

3. In a wood trimmer or the like, a table having a guideway, a member fixed to said table and having a guideway, a knife carrier supported in said guideways, knives at- 125 130

tached to said knife carrier, fences provided on said table and having slots and also angle markings, a canting table comprising a frame, the outer rail of which extends over
5 the outer edge of said fences and means passing through said slots for securing the canting table to the fences.

In witness whereof I have hereunto set my hand in the presence of two witnesses.

JOSEPH HOLLIS.
